UNITED STATES PATENT OFFICE.

GEORGE F. GIESECKE, OF LEIPSIC, SAXONY, GERMANY.

DESIGN FOR A FONT OF PRINTING-TYPE.

SPECIFICATION forming part of Design No. 14,571, dated January 29, 1884.

Application filed November 28, 1883. Term of patent 7 years.

To all whom it may concern:

Be it known that I, GEORGE F. GIESECKE, of Leipsic, in the Kingdom of Saxony, Empire of United Germany, have invented and 5 produced a new and original Design for a Font of Printing-Type, of which the following is a specification.

The nature of my design is clearly shown in the accompanying typographic impression, to 10 which reference is made; and it consists of a text-letter ornamented, as in the case of the A, B, D, F, H, I, J, K, L, M, N, P, R, U, and Y, by the heavy squares placed transversely, one 15 above the other, upon the left hand of the letter, and the faces of which are further ornamented by the vertical light lines, some of which, as in the A, F, K, M, N, P, and R, terminate in the rhomboidal ornament, as shown 20 at the lower termination, while in the letter Y the upper termination of the light line is ornamented by the rhomboidal termination.

In others of the letters, as in D, G, H, M, N, O, Q, V, and W, the faces are ornamented by the inclined light cross-lines placed one above the other, and connected by a small heavy figure, as shown.

The character of the design is preserved in the lower-case, the transverse square termination characterizing the terminations of the same, and the light vertical line, with rhomboidal termination, being found in the f, r, and t; and in the ff, fi, fl, and in the numerals—notably, the 1, 4, 7—the motive of the design is found.

Having now described my invention, I 35 claim as new—

The design for a font of printing-type, as shown and described.

GEORGE F. GIESECKE.

In presence of—

JOHN K. TETLOW,
F. WILKIE.
